UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A STANDARD FOR LIGHTING FIXTURES.

Application filed June 19, 1922. Serial No. 2,743. Term of patent 14 years.

To all whom it may concern:

Be it known that I, JOSEPH W. GOSLING, a citizen of the United States, residing at Schenectady, in the county of Schenectady, and State of New York, have invented a new, original, and ornamental Design for a Standard for Lighting Fixtures, of which the following is a specification, reference being had to the accompanying drawing, forming a part thereof.

The drawing is a front elevation of an ornamental standard of my invention for street lighting fixtures.

I claim:

The ornamental design for a standard for lighting fixtures as shown.

In witness whereof, I have hereunto set my hand this 16th day of June, 1922.

JOSEPH W. GOSLING.
